UNITED STATES PATENT OFFICE.

MILTON H. SHOENBERG AND GEORGE J. HENRY, OF SAN FRANCISCO, CALIFORNIA.

RADIANT ELECTRIC HEATER.

1,368,062.

Specification of Letters Patent.

Patented Feb. 8, 1921.

Application filed October 16, 1919. Serial No. 331,088.

To all whom it may concern:

Be it known that we, MILTON H. SHOENBERG and GEORGE J. HENRY, citizens of the United States, and residents of the city and county of San Francisco, State of California, have invented new and useful Improvements in Radiant Electric Heaters, of which the following is a specification.

Our invention has for its object the arrangement of parts so that a beam of radiant heat may be directed in any required angle in a vertical plane, also that the said beam may be laterally oscillated, or rotated. Other objects will appear from the description which follows.

In the heater of the present invention we prefer to arrange a heating element which will remain stationary during the lateral movement of the reflector, and substantially about the focus of said reflector, the oscillating or rotary movement taking place by the reflector independent of the heating element, and which reflector movement causes the rotation or oscillation of the radiating heat energy waves as a beam.

By referring to the accompanying figures the invention will be made clear.

Figure 1 is a side section of the assembled heater.

Fig. 2 is a front view of our heater with certain parts broken away to better show the structure of the joint means.

Throughout the figures the same numerals refer to similar parts.

The base frame or standard is indicated at 1. This base is preferably made hollow, and supports on its upper portion the heat radiating element 2, which is provided with electrical connections carried down through the hollow base and connecting from the source of electrical supply connected by the cord 5 in well known ways. Within the base is the vertical stem 6, carried on a roller bearing 7, and supported from internal brackets of the standard 1 as at 8. The stem also should be provided with a secondary or guide bearing as shown at 9, and I prefer to form this with a grease well as at 10. However, this bearing 9 may also be formed to

take end pressure if desired, and is then known in the art as a step bearing. Stem 6 is, however, restrained from lateral movement by the bearings 7 in the bracket 8, but is permitted to freely rotate, or oscillate, about its axis. Mounted at the upper end of the said stem 6 is the reflector arm 3, which

may be secured to the reflector, as by the rivets, or screws, at 4, and laterally braced as by the brace wires 13, 14. The means of connection between the stem 6 and the arm 3 is preferably that of a hinge joint as shown at 15, so that the reflector may be tilted on the said joint with respect to the stem 6; the said joint, however, is located substantially at the center of mass of the heating element 2 and approximately at the focus of 18, so that upon any swinging of the said reflector to its adjusted positions, it will at all times retain the heating element substantially at its focus.

The stem 6 may be oscillated by the mechanism 16, and motor 17; or suitable connections from the motor 17 to the stem 6 may be provided for the continued rotation of the said stem, so that the said movement will be transmitted through the joint 15 turning therewith the reflector 18 and consequently oscillating or rotating the beam of the heat projected therefrom.

The reflector 18 is to be cut away as shown at 19, so that it will suitably clear the standard 1 in its several adjusted positions. The joint 15 is to be provided with a swivel screw 23, so that the reflector may be clamped in its adjusted position, or other well known means may be employed as a substitute therefor.

We prefer to inclose the motor mechanism, when this is used, as indicated at 17, within the base of the standard 1, which may be suitably formed for receiving it, or it may be located externally and suitably connected through said base to the stem 6, and electrical connections to the motor not shown but well known, are to be furnished.

The heating element 2 is to be mounted on a suitably insulated base 20 from the standard 1, and while the annular form, which we have shown in the figure, is best suited to the heater where complete rotation is adopted, we do not wish to be confined to this form of heating element, as other forms may advantageously be employed, especially where oscillation of the heat beam is desired, as distinguished from complete rotation.

At 20 we have shown the wire guard screen, which is preferably attached to a ring adapted to engage within the flanged space 21 of the projecting flange 22, fitted to the periphery of the reflector 18, thus inclosing the heat radiating parts of the heater from accidental contact with inflammable

mable material, or personal injury. The 5 adjusted position of the reflector 18 by and at the joint 15 is retained by tightening the swivel bolt 23. The supporting arm 3 is to be provided with suitable braces to retain it rigid with respect to the reflector 18, and its area of connection at 4 with the heater may be made wider, or additional supports or struts may, if required, be interposed between 10 3 and 18.

It will be obvious that the curved surface of the reflector 18 is to be such a concave surface that, with a heating element of material size (as distinguished from a focal point) 15 there will be emitted radiant waves from the curved surface of the reflector in the form of a spreading beam. It is also obvious that the clearance requisite at 19 is to be such that in any required tilting position of the 20 reflector 18 it will nevertheless clear the standard or base 1.

We claim:

1. In an electrical heater, a heating element fixed upon a standard, and substantially at the focus of a heat reflector, a heat reflector supported from a standard and connecting adjustable means whereby it may be adjusted with respect to the standard, a wire guard cage forming inclosing means with the said reflector and inclosing the heating element and adjusting means of the said standard, and a stem supporting the reflector and cage from substantially the center of mass of the heating element.

2. In an electrical heater, a heating element fixed upon a standard, and substantially at the focus of a heat reflector, a heat reflector supported from a standard and connecting adjustable means whereby it may be adjusted with respect to the standard, a wire guard cage forming inclosing means with the said reflector and inclosing the heating element and adjusting means of the said standard, and a stem supporting the reflector and cage from substantially the center of mass of the heating element, and means whereby a rotative movement may be given the stem.

3. In an electrical heater, a heating element fixed upon a standard, and substantially at the focus of a heat reflector, a heat reflector supported from a standard and connecting adjustable means whereby it may be adjusted with respect to the standard, a wire guard cage forming inclosing means with the said reflector and inclosing the heating element and adjusting means of the said standard, and a stem supporting the reflector and cage from substantially the center of mass of the heating element, and means whereby a rotative movement may be given the stem, and means for adjusting the direction of the reflected heat beam in a vertical plane with respect to the axis of 60 the stem.

4. In an electrical heater, an electrical resistance heating element of symmetrical shape fixed to a standard, a concave reflector mounted with its focus substantially within the heating element; a base supporting 70 said standard and a rotatable joint between said reflector and said base with its axis of rotation coincident with the axis of the heating element.

5. Apparatus as set forth in claim 4 and 75 means for rotating the said reflector about the base.

6. Apparatus as set forth in claim 4 and 80 means for rotating the said reflector and standard, and a guard flange mounted on the periphery of said reflector of annular form and a plurality of guard wires from the said flange inclosing the heating element.

7. In an electrical heater, an electrical resistance heating element fixed to a base 85 standard, a concave reflector mounted with its focus substantially within the heating element; means supporting the reflector from a base and rotatably connected with said 90 base, and means for rotating the said reflector supporting means, and a guard flange mounted on the periphery of said reflector, of annular form, and a plurality of guard wires from the said flange inclosing 95 the heating element, and an enlarged passage way through said reflector and guard wires admitting relative adjustment about said base.

8. In an electric heater, a base and a reflector for radiant heat rotatably mounted on said base, the axis of said rotation passing substantially through the focus of said reflector, an electrical resistance heating element mounted on said base substantially 100 about said focus.

9. In an electric heater, a base and a reflector for radiant heat rotatably mounted thereon, the axis of said rotation passing substantially through the focus of said reflector, and electrical heating element mounted on said base substantially about 110 said focus, and a protective grating mounted from the periphery of said reflector and extending over the heating element on the 115 opposite side from the said reflector.

10. In an electric heater, a standard and a reflector for radiant heat rotatably mounted thereon, the axis of said rotation passing substantially through the focus of said reflector, a heating element mounted on said standard substantially at said focus, and electrical connections through 120 said standard and energizing said element.

11. In an electric heater, a base and a reflector for radiant heat rotatably mounted thereon, the axis of said rotation passing substantially through the focus of said reflector, a heating element mounted on said base substantially at said focus, and a pro- 125 130

5 tective grating mounted on the periphery of said reflector and extending over the heating element on the opposite side from the reflector, said reflector and said grating presenting concave surfaces toward said element.

12. In a radiant heater, a concave reflector for heat rays rotatably mounted on a standard, a heat emitting element rigidly mounted on said standard substantially at 10 the focus of the reflector.

13. In a radiant heater, a concave reflector for heat rays rotatably mounted on a standard, a heat emitting element mounted 15 substantially at the focus of the reflector

rigidly fixed to said standard, and electrical connections to said element.

14. In a radiant heater, a concave reflector for heat rays rotatably mounted on a standard, a heat emitting element mounted 20 substantially about the focus of the reflector and electrical connections to said element, in combination with a wire guard frame inclosing with the reflector the element therebetween.

In testimony whereof we have hereunto set our hands at San Francisco, California, this 9th day of October, 1919.

MILTON H. SHOENBERG.
GEORGE J. HENRY.
